Primary Examiner — Cathron Brooks*Assistant Examiner* — Christian P McLean*(74) Attorney, Agent, or Firm* — NSIP Law(57) CLAIM

We claim the ornamental design for a display screen or portion thereof with graphical user interface, as shown and described.

DESCRIPTION

The sole FIGURE is a front view of a display screen or portion thereof with graphical user interface showing our new design.

The outermost broken lines, showing a display screen or portion thereof, form no part of the claimed design. The remaining broken lines, showing portions of the graphical user interface, form no part of the claimed design.
